UNITED STATES PATENT OFFICE.

WILLIAM BUELL HALE, OF CHICAGO, ILLINOIS, ASSIGNOR TO WESTERN
ELECTRIC COMPANY, OF CHICAGO, ILLINOIS, A CORPORATION OF
ILLINOIS.

KEY FOR CABLE-TESTING.

SPECIFICATION forming part of Letters Patent No. 752,158, dated February 16, 1904.

Application filed April 29, 1901. Serial No. 57,952. (No model.)

To all whom it may concern:

Be it known that I, **WILLIAM BUELL HALE**, a citizen of the United States, residing at Chicago, in the county of Cook and State of Illinois, have invented a certain new and useful Improvement in Keys for Cable-Testing, of which the following is a full, clear, concise, and exact description.

My invention relates to a testing-key, and has for its object more particularly to provide an improved key by which the several circuit changes and connections incidental to measuring the electrostatic capacity and insulation resistance of cables may be effected with accuracy and rapidity.

I will describe my invention particularly by reference to the accompanying drawings, and the features which I regard as new will be pointed out in the appended claims.

2c Figure 1 is a view in elevation of the key of my invention, and Fig. 2 is a longitudinal sectional view thereof in association with a diagram illustrating the several circuit changes which may be effected by its use.

25 In the particular embodiment of my invention which I have chosen to illustrate, the main lever or switch-arm a is pivoted at its end to a metallic post b , mounted upon the top of an insulating - pillar. Three metallic contact-
30 posts d d' d'' are mounted upon insulating-
pillars in line with the switch-lever a , said posts carrying platinum contact-anvils c c' c'' , which are adapted to be engaged by corresponding contact-points of the switch-lever.

35 The contact-point a' , which is mounted on the under side of the switch-lever near its outer end, is adapted when the lever is depressed to strike the anvil c' of the post d' . The contact a^s is mounted on the upper surface of the lever and is adapted when the lever is in its elevated position to engage with the discharge contact-point c^s upon the end of the screw d , which is mounted on the post d^s . The spring b' tends to maintain the lever a normally in its elevated position, as shown in Fig. 2. A

40

45

third contact-point a^2 is carried by the point of a screw e , mounted upon a metallic spring f , which is screwed to the top of the switch-lever a . The end of the spring f is provided with an insulating-button g , by which it may be depressed. A stud g' , which may be the head of the screw fastening the insulating button or handle g to the spring, is mounted on the under surface of the spring in such a way that when the button g is depressed the stud g' will strike the surface of the switch-lever a , whereby both the contact-point a^2 and the switch-lever a may be depressed at the same time by simply pressing upon the button g . The spring f , with the contact carried thereby, thus constitutes what I term a "supplemental" or "auxiliary" key mounted upon the main switch-arm. Both the contact-anvils c and c^2 are preferably spring-mounted, as shown most clearly in Fig. 2. 65

shown most clearly in Fig. 2. A rocking lever h is mounted opposite the end of the switch-lever a , said rocking lever carrying an insulated detent or catch h' , which is adapted to engage the end of the switch-lever and hold it down when once said lever is depressed. This rocking lever h is yieldingly held over against the end of the switch-lever arm a by a spring k , as shown. Besides serving to hold down the switch-arm a the rocking lever h is adapted, when it is moved over to the right in releasing the lever, to bring a screw contact-point carried thereby into engagement with a spring-mounted anvil l . The adjustment of the several contact-points is such that when the lever is first depressed by pressing on the knob g the contact $a' c'$ will first be closed and then a moment afterward the contact $a' c'$ will be closed. Then on releasing the pressure the switch-arm a will be held down; but the spring or supplemental key f will be moved upward by its own resiliency a sufficient distance, so that the contact-point a^2 will be separated from the anvil c^2 . To release the switch-arm a , the rocking lever h is moved over to the right; 70 75 80 85 90

but the adjustment is such that the contact 7 will be closed before the switch-arm is released to make the contact $a^3 c^3$.

The operation of the key may be readily understood by considering Fig. 2. The contact-anvil c' is connected with a grounded source of current D, suitable for testing, and the post b, upon which the switch-arm a is mounted, is connected through the galvanometer G with the wire of the cable to be tested. The sheath of the cable, as usual, is grounded. The contact l controls a shunt around the galvanometer, including a predetermined resistance, to be used when the cable is discharged. The contact c^2 is connected to ground, and the contact c^3 is connected directly with the wire of the cable to be tested, so that when the contact $a^3 c^3$ is closed the galvanometer will be short-circuited.

In operating the key the knob g is first pushed down, so depressing the switch-arm a until both contacts $a^3 c^3$ and $a^2 c^2$ are made. Then on releasing the pressure the spring f moves up and separates the contact-points $a^2 c^2$, so that the current from the generator D finds path through the galvanometer to the wire of the cable being tested and thence to earth. By noting the deflection of the galvanometer the insulation resistance of the cable may be determined.

When the operator is ready to take the "capacity reading" of the cable, he pulls the discharge-release lever h, which first establishes at contact l the shunt-circuit about the galvanometer, including resistance R, and then releases the arm a, which moves up, breaking the battery connection c' and closing the discharge-contact c^2 . The cable acting as a condenser is thus discharged through the galvanometer and the shunt thereof, and by noting the deflection of the galvanometer the capacity may be determined. The resistance R of course is connected in shunt of the galvanometer, so that the deflection will be smaller than it would otherwise be, thus permitting the same galvanometer to be used for measuring both capacity and insulation resistance.

It is apparent that the ideas herein set forth may be embodied in structures differing to some extent from that shown in the drawings, and I do not desire to be understood as limiting myself to the particular device illustrated; but,

Having thus described my invention, I claim as new and desire to secure by Letters Patent—

1. In a testing-key, the combination with a main switch-lever, two switch-contacts operated in sequence in the movement of said switch-lever in one direction, a detent adapted to hold said switch-lever in its operative

position, a switch-contact operated in the movement of the detent, and a contact operated in the return of the switch-lever to its normal position.

2. In a testing apparatus, the combination with a source of current, a galvanometer and a shunt of the galvanometer including a resistance, of a main switch-lever, two switch-contacts operated in sequence through the agency of said lever when moved in one direction, one of said contacts controlling the connection of the source of current with the galvanometer and the device to be tested, and the other of said contacts controlling a short circuit of the galvanometer, a detent adapted to hold the switch-lever in its operative position, a switch-contact operated in the movement of the detent, said switch-contact controlling the said shunt of the galvanometer, and a contact actuated in returning the switch-lever to its normal position, adapted to discharge the device being tested, through the galvanometer.

3. In a switch-key, the combination with the switch-arm a and a contact adapted to be closed thereby, of a supplemental spring-mounted key f carried by said arm, an independent contact c^2 controlled by said supplemental key, the main switch-arm being adapted to be operated by operating the supplemental key, a detent or catch adapted to hold the switch-arm in one of its positions of adjustment, and a switch-contact controlled by said catch and operated in releasing the switch-arm a, substantially as set forth.

4. In a switch-key, the combination with a switch-arm a and a contact adapted to be closed thereby, of a supplemental spring-key f carried by said arm, and an independent contact c^2 adapted to be closed by said supplemental key, a knob g for said supplemental key, whereby both the supplemental key and the main switch-arm may be depressed; said supplemental key when released being adapted to break its contact c^2 independently of the switch-arm, a detent-lever h having a catch adapted to hold the arm a in its depressed position, and a switch-contact closed in releasing said arm.

5. In a testing apparatus, the combination with a source of current, a galvanometer and a resistance, of a key comprising a pivoted switch-arm and contacts closed in the alternate positions of said arm, one of said contacts controlling a connection of the source of current with the galvanometer and the cable to be tested, and the alternate contact controlling a connection of the cable through the galvanometer to a return-circuit to discharge the cable through said galvanometer, a supplemental switch-key carried by said switch-

arm, whereby the switch-arm and the supplemental key may be depressed together, a contact controlled by the supplemental key for closing a short circuit of said galvanometer, 5 the supplemental key being adapted to open said short circuit when released, a detent-lever for holding the switch-arm depressed, and a contact controlling a shunt of the galvanometer including the aforesaid resistance, closed

by said detent-lever in releasing the switch-arm.

In witness whereof I hereunto subscribe my name this 26th day of March, A. D. 1901.

WILLIAM BUELL HALE.
